UNITED STATES PATENT OFFICE.

WILLIAM P. THOMSON, OF LANSDOWNE, AND SAMUEL G. THOMSON, OF ALTOONA, PENNSYLVANIA.

RAIL-JOINT.

No. 821,378.

Specification of Letters Patent.

Patented Sept. 25, 1906.

Application filed February 15, 1905. Serial No. 245,683.

To all whom it may concern:

Be it known that we, WILLIAM PATON THOMSON, of Lansdowne, Delaware county, and SAMUEL GARVER THOMSON, of Altoona, Blair county, Pennsylvania, have invented a new and useful Rail-Joint, of which the following is a full, clear, and exact description, reference being had to the accompanying drawings, forming part of this specification, in which—

Figures 1 to 8, inclusive, are cross-sections showing different forms of our invention.

Our invention relates to that type of joint wherein splice-bars are provided with depending flanges extending below the rail-base. These flanges extend between the ties and may be cut off at the ties or may extend over them.

The object of our invention is to increase the moment of inertia and to provide a stiffer joint, also to strengthen and improve the shape of the depending flange and to provide against buckling under the strains.

In Fig. 1 we show the splice-bars 2 2 as provided with depending inwardly-inclined flanges 3 3, having enlargements or ribs 4 along the outer sides of either lower portion. The flanges are thus increased in thickness by the outer heads, giving a stiffer bar with a greater moment of inertia for the same amount of metal used. In Fig. 2 we show a similar form, in which the flanges 3^a are gradually increased in thickness toward their lower ends, forming substantially heads 35 which are enlarged on both sides of the central planes of the webs.

In Fig. 3 we show the flanges 3^b as depending in a vertical direction and having heads 4^b at the lower ends formed by enlarging the flanges on both sides.

In Fig. 4 we show the curved flanges 3^c as corrugated or reversely bent and provided with the enlarged ribs or heads 4^c.

In Fig. 5 we show our preferred form in which the curved flanges 3^d are given a concave form on the inner side and are provided with heads or enlarged portions 4^d, extending along their lower portions.

In Fig. 6 we show a form similar to that shown in Fig. 5, except that the curved flanges 3^e are reversely bent or corrugated and are provided with the heads 4^e.

In Fig. 7 we show a form similar to Fig. 6,

except that the curved flanges 3^f are bent to present convex faces on the inside, these 55 flanges having the heads 4^f.

In Fig. 8 we show a form similar to that shown in Fig. 3, except that the flanges 3^g are inclined inwardly and are provided with the heads 4^g.

In all the forms, the heads or ribs may be formed either on the inside or on the outside of the flange or upon both the inside and outside.

The advantages of our invention result 65 from the forming of the head by either the inside or the outside rib or the double rib for thickening, thus increasing the moment of inertia and giving a stiffer bar for a given amount of metal. The splice-bar is thus provided with a head along both edges on the same principle as a T-rail or I-beam, giving the greatest stiffness both vertically and laterally for a given amount of metal. The liability to buckling of the flange under the load 70 is greatly reduced, and the sections may be easily rolled. In the form shown in Figs. 5 and 6 the outward curve of the flange carries the strains around the foot of the rail more efficiently to the lower head than where a 75 sharp turn or small radius is present at the edge of the rail-foot. This larger radius also renders the rolling more easy. As shown in the drawings, our preferred structure consists of a flange the greater portion of the body of 80 which lies wholly outside of the line drawn from the junction of the flange proper with the foot of the rail and the inner edge of the foot of the flange. In case the flange merges into the foot of the rail as a gradual curve, as 85 shown herein, such point is the tangential point of the foot of the rail with such curve; but obviously the flange may meet the foot of the rail abruptly, in which case there is no tangential point.

Although we have shown our invention as applied to T-rails, it is just as easily applied to the girder or street-car forms.

Having thus described our invention, what we claim, and desire to secure by Letters Patent, is—

1. A splice-bar for rails having a freely-depending flange to extend below the base of the rail, said flange having a stiffening-rib on the inside at or near to its lower end.

2. A splice-bar for rails having a freely-de-

pendent flange to extend below the base of the rail, said flange having stiffening-ribs on both sides, forming a head, at or near to its lower end.

5. 3. A splice-bar for rails having a freely-dependent flange to extend below the base of the rail, said flange being curvilinear and concave on its inner side.

10. 4. A splice-bar for rails having a depending flange to extend below the base of the rail, said flange being of a corrugated or compound curved form.

15. 5. A splice-bar for rails having a depending flange to extend below the base of the rail, said flange being of a corrugated or compound curved form and having a stiffening-rib on one or both sides, forming a head at or near to its lower end.

20. 6. A splice-bar for rails having a depending flange to extend below the base of the rail, said flange being curvilinear and concave on its inner side and having a stiffening-rib on

one or both sides, forming a head at or near to its lower end.

7. A splice-bar for rails having a depending flange extending below the foot of the rail, the greater portion of the body of said flange lying wholly without the straight line drawn from the point of juncture of the flange with the foot of the rail, and the inner edge of the foot of the flange, the inner face of said flange consisting of a composite curve and having a stiffening-rib forming a head at or near the lower end. 25 30

In testimony whereof we have hereunto set our hands.

WILLIAM P. THOMSON.
SAMUEL G. THOMSON.
